(57) **CLAIM**

The ornamental design for a caulking device, as shown and described.

DESCRIPTION

FIG. 1 is a perspective view from above of my new design for a caulking device.

FIG. 2 is a front elevational view of the caulking device shown in FIG. 1.

FIG. 3 is a right side elevational view of the caulking device shown in FIG. 1.

FIG. 4 is a left side elevational view of the caulking device shown in FIG. 1.

FIG. 5 is a rear elevational view of the caulking device shown in FIG. 1.

FIG. 6 is a top plan view of the caulking device shown in FIG. 1; and,

FIG. 7 is a bottom plan view of the caulking device shown in FIG. 1.

The broken line elements depicting a drill in FIG. 1 are environmental, and form no part of the invention.
